UNITED STATES PATENT OFFICE.

ALFRED SCHOELLER, OF FRANKFORT-ON-THE-MAIN, GERMANY.

ELECTRIC CIGAR LIGHTER.

Application filed March 18, 1924. Serial No. 698,911.

To all whom it may concern:

Be it known that I, ALFRED SCHOELLER, a citizen of the German Republic, residing at Frankfort-on-the-Main, Germany, have 5 invented certain new and useful Improvements in Electric Cigar Lighters, of which the following is a specification.

This invention relates to an electric cigar lighter with removable heating wire carrier, 10 the heating wire being of such dimension that it can be sufficiently loaded with heat in order to permit of using the lighter separately from the source of current. The known devices of this type are composed of 15 a great number of parts, they are consequently expensive and not very secure in working or the heating body is not visible from the outside so that an unnecessary overheating takes place.

20 According to the invention a flat box-shaped heating wire carrier is removably mounted in a frame which leaves the heating body visible from the outside, the carrier being clamped in its position by means 25 of a spring which serves at the same time as a current bridge.

An embodiment of the invention is shown, by way of example, on the accompanying drawing, in which:

30 Fig. 1 shows the electric ignition body in section and in front elevation.

Fig. 2 shows in front elevation and in vertical section the switch which serves as current supplying socle.

35 Fig. 3 shows in front elevation and in vertical section the ignition body inserted in the switch-socle.

A is the casing for the box-shaped heating wire carrier. B is the heat insulating mass and D is the heating spiral. C is a bottom plate designed to insulate the heating spiral. F is the contact casing for the box-shaped heating spiral carrier. L are bars on the contact casing which form a 40 frame. K is a contact button for establishing the connection with the one pole of the current lead, the other pole being the

mass of the casing. This contact button K is acted upon by a blade spring G which serves for securely holding the heating 50 spiral carrier in the casing, the other end of said spring G serving to maintain the press button H normally in the switched out position. When the press button is pushed in it presses the lower end of said blade spring G against the contact plug J of the casing 55 whereby the circuit is closed.

The operation is as follows:—

The heating spiral carrier is inserted into the frame formed by the bars L and held in 60 this position by the pressure contact K and the spring G. If the press button H is pushed in the circuit is closed and current flows from the contact plug J through the spring G and the pressure contact K into 65 the heating spiral and thence back through the casing and the contact plug J. The heating spiral D being visible from the outside it can be seen at once when the heating spiral has been sufficiently heated whereupon the press button H is released. The heating spiral carrier can now be removed 70 from the casing and used for igniting a cigar.

I claim:—

Electric lighter for cigars comprising in combination a heating spiral carrier in the form of a flat box, a contact casing, a guiding frame on said contact casing for holding 80 said heating spiral carrier so that the heating spiral is visible from the outside, a pressure contact in the upper part of said casing, a press button in the lower part of said casing, a contact plug in the lower part of said casing opposite said push button and a blade spring fixed in said casing so that its upper end presses from behind against 85 said pressure contact and its lower end against said push button, said blade spring serving as contact between said contact plug and said pressure contact when said push button is pushed in.

In testimony whereof I affix my signature.
ALFRED SCHOELLER.
